UNITED STATES PATENT OFFICE.

JOHN M. ANCK, OF PHILADELPHIA, PENNSYLVANIA.

ELECTRIC RAILWAY.

SPECIFICATION forming part of Letters Patent No. 678,213, dated July 9, 1901.

Application filed April 24, 1901. Serial No. 57,239. (No model.)

To all whom it may concern:

Be it known that I, JOHN M. ANCK, a citizen of the United States, residing in the city and county of Philadelphia, State of Pennsylvania, have invented a new and useful Improvement in Electric Railways, of which the following is a specification.

My invention consists of an improved construction of electric-railway system, as hereinafter fully described and claimed.

Figure 1 is a longitudinal section of conduit for an electric-railway system embodying my invention, taken on line $x-x$, Fig. 3. Fig. 2 is a plan view thereof with a portion of the top of the conduit removed for convenience of illustration. Fig. 3 is a vertical transverse section of the conduit, taken on line $y-y$, Fig. 2. Fig. 4 is a side elevation of a portion of the flexible conductor.

Similar letters of reference indicate corresponding parts in the figures.

Referring to the drawings, A designates the body of the conduit, which is provided on its upper side with grooves B and B', in which the main feeder and flexible conductor are situated. Upon the upper side of the body A and closing the grooves B and B' is a cover C, suitably secured thereto. It is understood that the body A and cover C are formed of non-conducting material, such as wood, and mounted at one side of the cover C are the sections of the contact-rail D, said sections being separated by insulating portions E. These contact-rail sections D are connected with conductor-strips F, that extend into the conduit between the cover C and the upper edge of the body and along the lower face of the cover to the other side of the conduit, where they are electrically connected with sectional conductor G, secured to the lower face of said cover. Situated within the conduit is the main feeder H, that is protected by insulations J, such insulations extending in sections, as shown in Fig. 2, whereby said main feeder H can be connected with a flexible magnetic conductor K, situated on the other side of the conduit below the contact-strip G. The said flexible magnetic conductor K is hollow, as shown in Figs. 3 and 4, so as to reduce the weight thereof, and is connected with the main feeder H by means of resilient conductors L, consisting conven-

iently of springs, each being suitably connected at its opposite ends with said main feeder and flexible conductor. The magnet 55 M is carried by the car and travels over the flexible conductor, while the current-collector N travels in contact with the contact-rail D.

It is understood that my invention relates to that class in which the main feeder is inclosed within a closed conduit and the flexible magnetic conductor is raised to the top of the conduit in contact with the contact-sections by a magnet on the car and progressively as the car proceeds. The said flexible magnetic conductor thereby energizes such sections of the contact-rail that are in contact with the current-collector or over which the car is passing at the time, thereby avoiding a live contact-rail, and consequently 70 danger.

Having thus described my invention, what I claim as new, and desire to secure by Letters Patent, is—

1. In an electric railway, a closed conduit 75 composed of non-conducting material and having longitudinal grooves therein, a main electric feeder, and a flexible magnetic conductor electrically connected to said main electric feeder.

2. In an electric-railway system, a closed conduit, a main electric feeder therein, a flexible magnetic conductor therein, flexible connections between said main feeder and flexible conductor, a sectional conductor within 85 said conduit, situated over said flexible magnetic conductor, a sectional contact-rail exterior to said conduit, and electrical connections between the corresponding sections of said sectional conductor and contact-rail. 90

3. In an electric railway, a closed conduit, composed of non-conducting material and having a plurality of longitudinal grooves therein, a main electric feeder, a flexible magnetic conductor electrically connected to said 95 main electric feeder, means situated on the car to raise the said flexible magnetic conductor in contact with the sectional conductor within said conduit, a sectional contact-rail exterior to said conduit and electrical 100 connections between the corresponding sections of said sectional conductor and contact-rail.

4. In an electric railway, a conduit, a plu-

rality of longitudinal grooves therein, a main feeder located in one of said grooves, a hollow flexible conductor in the other of said grooves, an electrical connection between said feeder and conductor, and means for conveying electricity from said conductor to the desired point.

5. In an electric railway, a conduit, a plurality of longitudinal grooves therein, a main feeder located in one of said grooves, a flexible conductor in the other of said grooves, an electric connection between said feeder and conductor, and means for conveying electricity from said conductor to the desired point.
10. In an electric railway, a conduit having a plurality of grooves therein, a main feeder
15. 6. In an electric railway, a conduit having a plurality of grooves therein, a main feeder

located in one of said grooves, insulation for said main feeder, a flexible magnetic conductor in the other of said grooves, an electrical connection between said feeder and conductor, and means for actuating the latter.

7. In an electric railway, a conduit having a plurality of grooves therein, a main feeder located in one of said grooves, insulation for said main feeder, a flexible magnetic conductor in the other of said grooves, a coiled spring forming an electrical connection between said feeder and conductor, and means for actuating the latter.
